UNITED STATES PATENT OFFICE.

CHARLES H. ANDERSON AND THOMAS ELLIOTT, OF CINCINNATI, OHIO.

WINDOW FOR VESTIBULES OF STREET-CARS.

1,153,008.

Specification of Letters Patent.

Patented Sept. 7, 1915.

Application filed October 9, 1914. Serial No. 865,902.

To all whom it may concern:

Be it known that we, CHARLES H. ANDERSON and THOMAS ELLIOTT, citizens of the United States, and residents of Cincinnati, 5 in the county of Hamilton and State of Ohio, have invented certain new and useful Improvements in Windows for Vestibules of Street-Cars; and we do hereby declare the following to be a full, clear, and exact 10 description of the invention, such as will enable others skilled in the art to which it appertains to make and use the same.

Our invention relates to an improvement in windows for the vestibules of street cars, 15 the object being to provide improved means for opening and closing the center window of the vestibule or front platform of a car, the construction being such that when the window is closed, it will be flush with the 20 other windows and practically air and water tight; and when open it will rest at the rear of and parallel with one of the side windows of said vestibule.

With these objects in view our invention 25 consists in the parts and combinations of parts and in the details of construction as will be more fully described and pointed out in the claims.

In the accompanying drawings Figure 1 30 is a view in elevation of our improvement. Fig. 2 is a view in side elevation of the center or sliding sash. Fig. 3 is a view in plan of the rails supporting said sash. Fig. 4 is a view in plan showing the guiding and locking 35 means for the lower end of the sash. Figs. 5 and 6 are views of the hangers. Figs. 7 and 8 are views of the cranks which are carried by the hangers, and Figs. 9 and 40 10 are views of the guiding and locking device vice at the lower end of the sash.

The front vestibule or platform of the modern street car is curved at its front end, and is provided with three windows, one of which is at the center and in front of the 45 motorman. It has been customary to provide means for opening the center window by sliding the center sash laterally, or by lowering it into a pocket in the dash board. With the laterally sliding windows, it has 50 been impossible to make them fit flush and close when closed, so as to exclude air and water, and with the vertically sliding window, the pocket into which it drops is always exposed or open to the water falling 55 against the window.

Our improvement consists of a center sash

1 provided at its top edge with the hangers 2 which latter are mounted on the rod 3, which is slightly shorter than the width of the sash. Secured to the ends of the rod 3 60 are the cranks 4 and 5, the crank 4 being of ordinary form, and the crank 5 of the bell-crank type, the latter being shown in detail in Figs. 7 and 8. These cranks are journaled in the sleeve ends 65 6^a of screws 6, and the latter are screwed into the hangers 7, each of which latter is provided with a wheel 9 resting in the grooved track 10, secured by brackets 11, to the window frame at the top thereof as 70 shown in Fig. 2. The hangers 7 are shaped as shown so as to permit the screws 6 to rest in the vertical planes of the wheels 9, and when the window is in its closed position, its upper end and the horizontal rod 3, to which the sash is connected, are in a vertical 75 plane to the front of the wheels 9 as shown in Fig. 2.

Bell-crank lever 5 is journaled at 5^a to its screw 6, while rod 3 is secured to elbow 5^b 80 of said lever. Secured to the free end of the smaller arm 5^c of said lever 5, is the actuating rod 10^a which extends downwardly in rear of sash 1 to near the lower end of the latter. This rod is preferably located 85 within a groove in the sash and covered by a plate, but it may be removed from the sash and wholly exposed, as this detail is immaterial.

Rod 10^a is connected at its lower end at 11^a. 90 to the lever 12 which is pivoted at 13 to the bracket 14 secured to the side rail of the sash near the lower end of the latter. This lever 12 normally rests in a vertical position as shown in Fig. 2, and is provided 95 with a shoulder 15, which comes in contact with the bracket 14 after the lever has been turned 45°, or to a horizontal position, and forms a rigid handle for manipulating the sash. The sash, when in its closed position, 100 rests against the inner face of the top of the frame and on the sill 16, as shown in Fig. 2, the sill being preferably downwardly inclined so as to shed water.

With the construction thus far described 105 it will be seen that by grasping the lever 12 and turning same to a horizontal position, the rod 10^a will be pulled downwardly and turn the bell-crank 5 on its fulcrum 5^a. This turning movement of the bell-crank 110 elevates the window sash 1, and moves same rearwardly or toward the motorman, thus

freeing it from its seat in the frame. The partial rotation of the bell-crank 5 also turns rod 3, and the crank 4 on the other end of same, thus moving both sides of the sash simultaneously and in the same direction. The upward pull on lever 12, also tends to lift sash 1 and consequently assists the turning movement of the bell-crank lever 5. After the sash has been moved inwardly sufficiently to clear the window frame, it is moved to the left by pushing on lever 12, thus causing the wheels 9 to travel in the grooved track 10. One section of the track 10 is parallel with the center window, and the other parallel with the side window, the two sections of the track being at an oblique angle as shown in Fig. 3. The wheels 9 are free to follow the tracks by reason of their screw connection with the crank-levers 4 and 5. With this construction the center sash can be readily and quickly shifted from its closed to a wholly or partly open position or back again to its closed position, and when closed, it makes a fit sufficiently close with the sash to prevent the entrance of either air or water.

The mechanism for locking the sash at its lower end, consists of a bracket 17 slotted centrally as at 18, and provided with the 30 parallel horizontal flanges 19 located respectively above and below the slot, and to which the hinge member 20 is pivoted, the pivot of the latter being so located with relation to the rear wall of the slot 18, as to 35 permit of a limited rearward or inward movement of the hinge member. The opposite end of the hinge member 20 is enlarged as at 21, the enlarged part being rounded and hollowed on its front side for the reception of the vertical pin 22, on which the 40 guide block 23 is mounted to turn, and also move vertically. The enlarged end 21 of the hinged member is provided at its upper end with the laterally projecting integral 45 shoulder 24, adapted to engage a cam surface 25 on the guide block 23, and also engage the rearwardly projecting inclined rib 26 on the guide block during the final closing movement of the sash. The bracket 17 50 is secured to the lower (and in the present instance) left hand corner of the sash 1, and the guide block is mounted to slide on the flat rail 27, secured at the rear of the left hand side sash 28. When the sash 1 is 55 closed, the shoulder 24 on the hinge member 20, rests in contact with the rib 26, and the hinge member is in contact with the rear wall of slot 18 in bracket 17. When lever 12 is grasped and turned to a horizontal 60 position, the upward movement of the sash 1, carries with it the bracket 17 and hinge section 20, thus lifting said parts, until the shoulder 24 is in a plane above the cam 25, thus permitting of sufficient flexibility 65 between the parts composing the combined

lock and guide, for the lower end of the sash to move inwardly or rearwardly and also turn onto the guide rail 27. After the sash has been moved to open position, the release of the lever 12, permits it to move 70 forwardly toward and if desired into contact with sash 28.

To close the sash, the lever 12 is operated as previously explained thus lifting the sash and moving the same rearwardly, 75 after which it is pulled to its central position in the end of the vestibule. By now releasing the lever 25, and pushing down on same if necessary, the sash 1 will be moved forwardly and downwardly into its 80 seat in the frame. As the sash descends the shoulder on the hinge section of the combined lock and guide moves in contact with the cam face of cam 25, which operates to force the bracket 19 and the lower end of 85 the sash to which the bracket is secured, forwardly or outwardly, and when the latter is seated on the sill 16, the shoulder 24 will be in the plane of rib 26, thus locking the lower end of the sash against inward 90 movement and prevent it from rattling.

With this improvement, the sash can be readily and quickly shifted by the motor-man from one position to the other, and when in its closed position, it makes a close 95 fit with the frame and sill.

It is evident that changes in the construction and relative arrangement of the several parts might be made without avoiding our invention and hence we would have it understood that we do not restrict ourselves to the particular construction and arrangement of parts shown and described, but,—

Having fully described our invention what we claim as new and desire to secure 105 by Letters Patent, is:

1. The combination of a window frame and sash, means for moving the sash rearwardly away from its seat on the frame, traveling hangers carrying said moving 110 means, and combined lock and guide carried by the sash at its lower end, one part of said lock and guide having a pivoted and sliding movement on the other part, the said other part having sliding engagement with 115 a fixed rail located at one side of the frame.

2. The combination of a window frame and sash, means for moving the sash rearwardly away from its seat in the frame, traveling hangers carrying said moving 120 means, and a combined lock and guide carried by the sash at its lower end and having sliding engagement with a fixed rail located at one side of the frame.

3. The combination of a window frame 125 of a car vestibule, a trackway located in a plane above said window and also at one side thereof, hangers mounted to travel on said trackways, a sash carried by said hangers, a fixed rail adjacent the lower edge and 130

- at one side of said window and a combined lock and guide carried by the sash at its lower end, one part of said lock having a pivoted and also a sliding movement on 5 the other part, and the said other part having a sliding engagement with the said rail.
4. The combination of a frame, sash, traveling hangers supporting the sash at the upper end of the latter and jointed guiding 10 means composed of parts having pivotal and sliding connection with each other one of said parts being secured to the sash near the lower end of the latter and another part engaging a fixed guide rail whereby 15 the lower end of the sash will be guided and retained against swinging movement.
5. The combination of a frame, sash, traveling hangers supporting the sash and means connecting the sash and traveling 20 hangers whereby the sash may have an upward and inward movement on its hangers, and a guide and lock composed of parts pivotally and slidably connected for guiding the lower end of the sash in its vertical and 25 lateral movement and for locking it in its closed position.
6. The combination of a frame, sash, traveling hangers supporting the sash and means connecting the sash and hangers 30 whereby the sash may be moved upwardly, and inwardly away from its seat in the frame, and a guide and lock composed of
- parts having pivotal and sliding connection, one of said parts being secured to the sash and having sliding connection with a fixed 35 rail for guiding the lower end of the sash in its lateral movement and for locking it against rearward movement, when in its closed position.
7. The combination of a frame, sash, 40 traveling hangers supporting the sash and means connecting the sash and hangers whereby the sash may be moved upwardly and inwardly away from its seat in the frame, and a combined lock and guide comprising a member secured to the sash, a member engaging a fixed guide rail, and a third member pivotally connecting the other members, the said member which engages the fixed rail and the connecting member, having engaging parts which lock the sash in its closed position and which necessitates a lifting of the sash before the latter can be moved to open position. 50
- In testimony whereof, we have signed 55 this specification in the presence of subscribing witnesses.
